LOCK

Filed July 19, 1913

2 Sheets-Sheet 2

By his Attorney Oscar Geier

UNITED STATES PATENT OFFICE.

ADAM POSTEMSKY, OF WILLIMANTIC, CONNECTICUT.

LOCK.

Application filed July 19, 1918. Serial No. 245,641.

To all whom it may concern:

Be it known that I, ADAM POSTEMSKY, a citizen of Russia, residing at Willimantic, county of Windham, and State of Connecticut, have invented certain new and useful improvements in Locks, of which the following is a specification.

The invention relates to an improvement in locks of the type involving a locking bolt and a latch bolt, and is directed to the provision of means requiring the adjustment of permutation elements to permit movement of the lock bolt and the following adjustment of a permutation element to actuate the lock bolt.

The invention generally indicated comprises a lock bolt having projections engaging the periphery of permutation discs to prevent unlocking movement of the bolt, the discs being arranged in sets and separately controlled according to a predetermined arrangement to arrange radial slots in said discs in line with the bolt to permit its movement. Bolt operating means are provided which is normally beyond the action of the user and which is set for such action by the user through a predetermined series of movements of the operating member. The latch member of the lock, which is normally free for operation from the inner side of the part carrying the lock, is also adapted to be operated by the bolt operating means following the predetermined movements of the latter necessary for operating the lock.

The invention is illustrated in the accompanying drawings, in which:

Fig. 1 is a view in side elevation illustrating the application of the lock.

Fig. 2 is a transverse section taken on the line 2-2 of Fig. 3.

Fig. 3 is a vertical section taken through the door or other part carrying the lock and showing the parts of the lock substantially in elevation.

Fig. 4 is a section on line 4-4 of Fig. 3.

Fig. 5 is a transverse sectional view through the lock showing particularly the means for connecting the operating member with the lock bolt operating means.

In the drawings, the lock is shown as mounted in a door 10, the frame 11 of which is provided with the usual keeper 12. The lock proper includes a metallic casing having side walls 14 and 15 and a cover

plate 16 adapted as is usual to extend beyond the casing to permit securing of the lock, as by fastenings 17 in the usual mortise in the edge of the door. Slidably mounted within the casing is a locking bolt 21 having locking lugs 20 projecting at right angles thereto and when in locking position extending through the cover plate to engage the keeper.

The locking bolt 21 is formed within the casing near the respective ends thereof with transverse bar sections 23 and 24, and these sections are adapted to overlie and bear upon the peripheries of independent sets of discs, the engagement of the bars with the peripheries of the respective sets of discs holding the locking bolt 21 in position to maintain the locking lugs 20 in operative or locking positions. The respective sets of discs are in duplicate, the lower set for example involving an inner disc 25 fixed upon a spindle 28 supported in a boss 29 projecting from the side wall of the casing and in a sleeve 33 secured to the front wall of the casing. An intermediate disc 26 and a forward disc 27 are loosely mounted on the sleeve 33 and held in spaced relation by collars 34. The discs 25, 26, and 27, are formed with radial slots 37, 38, and 39 respectively, which extend through the peripheries of the disc, and when in alignment transversely of the casing and in register with the projection 24, providing an opening to permit movement of said projection 24 and hence the locking bolt 21 inwardly, to move the locking lugs 20 to an unlocking position, assuming that the upper set of discs has been correspondingly arranged. The spindle 28 projects beyond one side wall of the casing in the form of an operating knob 31, which may be provided with a pointer or other indicator for movement over a dial 30 to determine the positions of the respective discs. Disc 26 is provided with projections 40 extending at right angles thereto and adapted to be engaged by and engage projections 42 from disc 25 and a projection 43 from disc 27. This arrangement provides a simple form of permutation control of the discs, and it is obviously apparent that through manipulating the discs through successively reversed movements of the knobs 31, the discs may, at will, be arranged to permit movement of the locking

110

bolt 21 so far as the projection 24 is inserted. The upper set of discs 25', 26', and 27', are duplicates of the lower set of discs, the disc 25' being connected to a spindle 28' 5 mounted at one end in a boss 29' projecting from the side wall of the casing and also in a sleeve 33' projecting from the opposite side wall, the spindle extending through said latter side wall and having 10 an operating rod 31' cooperating with the dial 30'. This upper set of discs includes discs 26' and 27', the former provided with projections 40' to cooperate with projections 42' and 43' from the discs 25' and 27', said 15 discs 26' and 27' being loosely mounted on the sleeve 33' and held in spaced relation by collars 34', and said discs 25', 26', and 27', being formed with radial notches 37', 38', and 39', which when the upper set of 20 discs is operated according to a predetermined movement of the dial, the notches in these discs will be arranged to permit movement of the upper projection 23 of the locking bolt.

25 Obviously therefore, the locking bolt is normally held against movement when in locking position by the peripheral edges of the discs, and the movement of the locking bolt is permitted only following proper set 30 or arrangement of both the upper and lower sets of discs.

The means for operating the lock bolt includes arms 45 and 46 projected inwardly from the lock bolt 21 and arranged in spaced relation, being guided in a frame 48 supported by brackets 49 projecting from the side wall of the casing. An operating spindle 57 is mounted for longitudinal sliding movement in 35 that side wall of the casing carrying the dials 30 and 30'. This spindle has an operating handle 64 adapted for cooperation with a dial 65 and on the spindle and between the inner surface of the side wall of 40 the casing and the handle 64 is a coil spring 68. An open bracket 63 tends to support the shaft and also to limit the inward position of the handle 64, the wall of the casing being formed with an opening of sufficient size 45 to permit the movement of the handle knob 64 therethrough. Rotatively supported upon the spindle 57 and held against other than 50 rotative movement in the frame 48 is a gear pinion 55, the teeth of which are adapted to engage teeth 54 formed on the upper arm 45 leading from the lock bolt, so that upon 55 turning of the pinion, the lock bolt may be withdrawn or projected at will. The pinion is formed with a radial slot 71 and a disc 56 60 is rotatively supported upon the spindle 57 immediately in advance of the pinion 55, this disc being formed with a corresponding slot 72 and with an axial projection 70 on its front face. The spindle 57 is provided with 65 a laterally extended operating member 69

preferably in the form of a loop and of a size to readily enter the slots 72 and 71 when the latter are aligned.

Supported in brackets 52, 53, projecting from the inner side wall of the casing is a latch bolt 50, normally spring pressed in latching position, that is, with its nose beyond the front wall of the casing to engage the keeper. This latch bolt is normally retracted through the medium of an operating member 58 having an operating knob 59, with said member 58 rotatably mounted in the side wall of the casing in line with and being formed with a bore to slidably receive the end of the spindle 57. The member 58 is connected with the latch bolt so as to retract the latter at will upon turning of the knob 59, and the spindle 57 is provided with a laterally projecting pin 61, which when the spindle is in position to operate the pinion 55, as hereinafter described, is adapted to engage one or the other of the serrations 60 in the end of the latch operating member 58 to thereby cause said latch operating member to turn with the spindle.

The latch 50 and adjacent wall of the casing are provided with openings to receive a removable pin 51, which when inserted through the opening in the casing and taking into the latch bolt, prevents any movement whatever of the latch bolt.

In operation assuming that the person desiring to open the lock is familiar with the various combinations required, the upper and lower sets of discs described will be arranged in their predetermined relative positions to so align the slots in the disc as to permit movement of the lock bolt 21. The spindle 57 is then pressed inwardly against the tension of the spring 68 until the element 69 has been moved into the path of the projection 70 on the disc 56. Following this engagement, the spindle 70 is moved to a predetermined position governed by the dial, at which position the slot 72 in the disc 56 and the slot 71 in the pinion 55 will register. The spindle 57 is then moved farther inwardly to cause the member 69 to enter the slots 72 and 71, locking the pinion 55 to the spindle 57. Turning movement of the spindle in the opposite direction will then obviously actuate the locking bolt 21 to withdraw the locking lugs 20 from the keeper. When the spindle has been moved to pinion operating position, the pin 61 on such spindle will engage one of the serrations 60 of the latch operating member 58, so that as the spindle is turned to operate the locking bolt, the latch will also be withdrawn. If, however, it is desired that the lock shall not be operated even with a knowledge of the combination, the pin 51 may be introduced into the latch, preventing movement of the latter, and as the locking bolt operating spindle cannot be turned

without operating the latch, the fixing of the latch against movement prevents operation of the lock.

What I claim is:

- 5 1. In a lock, a locking bolt, independent sets of tumblers for controlling the movement of said locking bolt, an operating member for the locking bolt, and means adapted to interlock with said member for operating
10 the same, said means being normally free of the member and adapted to be positioned for interlocking therewith in a predetermined relative arrangement of the member and said means.
- 15 2. In a combination lock, a casing, a locking bolt operative therein, tumblers for controlling the movement of the locking bolt, a pinion for operating the locking bolt, and a spindle for operating the pinion, said
20 spindle being normally free of the pinion and adapted to interlock therewith in a predetermined relative arrangement of the parts.
- 25 3. In a combination lock, a casing, a locking bolt operative therein, tumblers for controlling the movement of the locking bolt, a pinion for operating the locking bolt, a spindle for operating the pinion, said spindle being normally free of the pinion
30 and adapted to interlock therewith in a predetermined relative arrangement of the parts, a latch bolt mounted in the casing, means for operating the latch bolt, and a connection between said spindle and latch
35 bolt operating means when the spindle is in operative relation with the pinion.
4. In a combination lock, a casing, a locking bolt operative therein, tumblers for controlling the movement of the locking bolt, a pinion for operating the locking bolt, a spindle for operating the pinion, said spindle being normally free of the pinion
40 and adapted to interlock therewith in a predetermined relative arrangement of the parts, a latch bolt mounted in the casing,
45
- means for operating the latch bolt, a connection between said spindle and latch bolt operating means when the spindle is in operative relation with the pinion, and means for locking the latch bolt against movement. 50
5. In a combination lock, a lock bolt, spaced sets of tumblers for controlling the movement of the lock bolt, a pinion for operating the lock bolt and formed with a radial recess, a disc mounted in advance of 55 the pinion and formed with a similar recess, a spindle slidable axially of the disc and pinion, and means whereby the spindle may operate the disc to align the slots in the disc and pinion, said spindle being longitudinally movable to permit the passage of said disc operating element into the aligned slots of the disc and pinion, whereby to interlock the spindle and pinion to compel operative movement of the lock bolt in the 60 movement of the spindle.
6. A latch bolt, an operating member therefor, a spindle on which the operating member is mounted, a locking bolt, a pinion for operating the locking bolt, said spindle 70 being adapted to interlock with the pinion at will, and means on the spindle to interlock with the operating member of the latch bolt when said spindle is in a position to interlock with the pinion. 75
7. A latch bolt, an operating member therefor, a spindle on which the operating member is mounted, a locking bolt, a pinion for operating the locking bolt, said spindle being adapted to interlock with the pinion 80 at will, means on the spindle to interlock with the operating member of the latch bolt when said spindle is in a position to interlock with the pinion, and a pin to engage with the latch bolt to prevent movement 85 thereof, whereby to lock the parts against operation.

In testimony whereof I have affixed my signature,

ADAM POSTEMSKY..
